(57) CLAIM

The ornamental design for a “wrist exerciser with handle,” is as shown and described.

DESCRIPTION

FIG. 1 is a perspective view of wrist exerciser with handle showing our new design;

FIG. 2 is a front view thereof;

FIG. 3 is a rear view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is another perspective view of the wrist exerciser with handle showing our new design in an alternative position.
